UNITED STATES PATENT OFFICE

ROLAND O. RUBLE, OF ROSEDALE, KANSAS

AUTOMOBILE SIGNAL SWITCH

Application filed July 11, 1927. Serial No. 204,829.

My present invention pertains to automobile signal means, and contemplates the provision of means whereby a visual signal will be flashed at the rear of an automobile when the driver of the automobile lessens pressure on the accelerator pedal.

To the attainment of the foregoing, the invention consists in the improvement as hereinafter described and definitely claimed.

10 In the accompanying drawing forming part of this specification:

Figure 1 is a view partly in section, and partly in elevation illustrating the preferred embodiment of my invention.

15 Figure 2 is a top plan view of the same.

Figure 3 is a view diagrammatic in character and illustrating by way of example a signal circuit that may be employed.

20 Similar numerals of reference designate corresponding parts in all the views of the drawing.

I show in Figures 1 and 2 a portion of the floor board 1 of an automobile, the said board being apertured at 2 for the passage and play 25 of an accelerator pedal, designated by 3.

The accelerator pedal shown is of lever type, but I would have it understood that within the purview of my invention the accelerator pedal may be of any other type com-

30 patible with the purpose of my invention.

In furtherance of my invention a base plate 4 is fixed on the floor board 1, and fixed with respect to the plate 4 and preferably insulated therefrom is a conductive standard 5 having 35 at its upper end a terminal 6.

The plate 4 is also equipped with a standard 7, and pivotally connected at 8 to the standard 7 is a lever 9 subject to the action of a spring 10 and provided at 11 with a terminal 12 opposed to the before mentioned terminal 6. The spring 10 is relatively arranged as illustrated and therefore its tendency is to press the terminal 11 against and hold said terminal 11 in contact with the terminal 6 so as to cause to glow the filament in an incandescent electric lamp 12, designed to be carried at the rear of an automobile.

Within the purview of my invention any desired circuit may be employed including the 45 terminals 6 and 11, the lamp 12 and a source

of electric energy, designated by 13, and I also prefer that the said circuit include a hand switch as designated by 14 in Figure 3 so that the circuit may be interrupted independently of my improvement when the automobile is 55 not in use.

The free portion of the lever 9 and what may be properly designated the pedal portion thereof is arranged alongside of and closely adjacent to the accelerator pedal 3 as design-

60 nated by 15 in Figures 1 and 2, and consequently it will be understood that when the driver of the automobile depresses the accelerator pedal 3 with his foot, he will also de-

press the free portion of the lever 9 and in 65 that way move the terminal 11 away from the terminal 6. When however, the accelerator pedal 3 is relieved of pressure, the lever 9 will likewise be relieved of pressure and in consequence the spring 10 will promptly 70

swing the lever 9 upwardly and move the terminal 11 into contact with the terminal 6 and cause the filament in the lamp 12 to glow, with the result that a warning will be flashed to the driver behind very much more quickly 75 than is the case when the tail light or tail signal is operated from the brake lever of the automobile.

It will be apparent from the foregoing that so long as the accelerator pedal is subjected to 80 downward pressure, the lamp 12 will be idle, but just as soon as the pedal lever or pedal 3 is relieved of pressure precedent to diminishing the speed of an automobile, the circuit indicated will be closed by the contact of the 85 terminal 11 with the terminal 6 and the filament in the lamp 12 will be caused to glow.

It will also be apparent that my improvement is simple and inexpensive in construction, and is susceptible of being easily and 90 economically installed in a conventional automobile, or any other automobile having an accelerator pedal.

I have entered into a detailed description of the construction and relative arrangement 95 of parts embraced in the present and preferred embodiment of my invention in order to impart a full, clear, and exact understanding of the embodiment. I do not desire, however, to be understood as limiting myself to the 100

construction and arrangement disclosed, my invention being defined by my appended claim within the scope of which modifications may be made without departure from my invention.

5 Having thus described the invention, what I claim is:—

In automobile signal means, and in combination, terminals, one of which is movable below and toward and from the other, an automobile accelerator pedal in rear of said terminals, a standard carrying the terminal opposed to the movable terminal, a lever carrying said movable terminal and fulcrumed in front of the terminals and having a rear portion arranged alongside of and in close proximity to the accelerator pedal and adapted to be depressed when the accelerator pedal is depressed, and yielding means. 10 below and exerting upward pressure against the lever forward of the terminals for moving said lever and putting the movable terminal in contact with the other terminal when the accelerator pedal is relieved of pressure. 15

20 25 In testimony whereof I affix my signature.

ROLAND O. RUBLE.
